UNITED STATES PATENT OFFICE.

JAMES W. McDONOUGH, OF NEW YORK, N. Y.

TELEPHONE.

SPECIFICATION forming part of Letters Patent No. 438,818, dated October 21, 1890.

Application filed March 9, 1888. Serial No. 266,663. (No model.)

To all whom it may concern:

Be it known that I, JAMES W. McDONOUGH, a citizen of the United States, residing at New York, in the county and State of New York, have invented certain new and useful Improvements in Apparatus for Electrically Transmitting Articulate Speech and other Sounds, of which the following is a specification, reference being had to the drawings accompanying and forming a part of the same.

My invention relates to a method of telephoning; and it consists in the appliances and apparatus made use of in carrying out the same.

The invention is more particularly applicable to long-distance telephony or systems in which telephonic intercommunication is established over circuits of great length; but it is capable of being used generally under practically the same conditions as other telephones.

To accomplish the objects of my invention I seek to produce on the line leading to the receiving-instrument a rapid succession of distinct and separate electrical impulses constituting what is known as an "intermittent current." To produce a current of this character capable of acting on a telephonic receiver so as to cause it to reproduce articulate speech, I use, in conjunction with certain other appliances hereinafter set forth, one or more condensers. These devices constitute in their combination the transmitter proper, and for the receiver I employ any of the ordinary telephonic receivers now in use. The transmitting mechanism is so organized that it takes up a battery-current, as varied or modified by the human voice or by any other sound through the instrumentality of a suitable device, and transfers it from the local circuit to an independent or separate line or circuit leading to the receiver, at the same time converting it into an intermittent current. For this purpose I use in combination with one or more condensers a circuit shifter or controller acting to connect the plates or poles of the condenser or condensers alternately to the local circuit and the main line, or, in other words, alternately to charge the condenser by the varied local current and to discharge it into the line. Inasmuch as the time required for a condenser to discharge is very much less

than that which, under these circumstances, at least, is required to charge it, it is evident that the current, whatever its condition or character may be in the local circuit, consists, when delivered to the main line, and thus when it reaches and acts on the receiver, of a succession of independent separate impulses or discharges, and that these vary in their intensity and consequently in their effect upon the receiver with the varying strength of those portions of the local current to which said impulses respectively correspond, and so with the varying strength of the corresponding parts of the air vibrations, which, by their action on the transmitting mechanism, give character to the local current. This being the general character of the means by which the invention is carried into effect I will now, by reference to the drawings, explain the details of the same and indicate in what ways they may be modified.

Figure 1 shows in perspective the exterior of one form of the apparatus when arranged for use. Fig. 2 is a partly diagrammatic view of a simple form of the transmitting apparatus. Fig. 3 is a perspective view with diagrammatic connections of a modified form of transmitter. Fig. 4 is a diagram of the details and circuit-connections of Fig. 3. Fig. 5 is a modification of the same. Fig. 6 is a plan view of another modified form of apparatus, containing also the circuit-connections diagrammatically shown.

Referring to Fig. 2, which serves to illustrate the principle of operation of the invention generally, L L represent a main line or circuit containing an ordinary telephonic receiver R. The means for modifying or varying the current to operate the receiver comprise the remaining appliances shown. Of these T is a microphone or any other telephonic instrument capable, when acted on by the human voice or by other sounds, of producing changes in the local current corresponding to the sound-waves that excite it. It is included in the local circuit t' with a battery B and the primary C of an induction-coil.

I mount in a suitable box or frame A''' a metal disk A, which may be revolved at high speed by a train of gears A' driven by springs, weights, or otherwise. The periphery of this

wheel or disk is serrated, and insulating-blocks are fitted in between the teeth, forming a smooth and even peripheral surface. Two contact-springs *b c* bear upon the periphery of the wheel, and a third contact-spring *a* bears upon the side of the disk or upon the circular shoulder thereon, in the manner illustrated. The contacts *b* and *c* are so disposed that both are never in contact with the metal at the same time. The spring *a*, on the other hand, being always in contact with the disk, is brought alternately into electrical connection with the springs *b* and *c*. One end of the wire or circuit *S*, including the secondary *C'* of the induction-coil, is connected to one of the contact-springs, as *b*, and the other end of the conductor *S* is connected to one of the terminals of a condenser *D*. In like manner the ends of the circuit *L* are connected, respectively, to the same condenser terminal and to the other contact-spring *c*. A wire *S'* connects the opposite terminal of condenser *D* with the contact-spring *a*. The operation of this system is as follows: The disk *A* is set in rapid uniform rotation. Then by speaking into the instrument *T* the local current in the primary wire *t'* of the induction-coil is varied or modified, and the changes thus produced in the intensity of this current excite currents in the local secondary circuit *S S'*. These secondary currents, however, do not pass to the receiver *R*, but flow into the condenser whenever the spring *b* is in contact with the metal teeth of the disk *A*. When the spring *c* comes in contact with one of the metal teeth, the condenser is discharged into the main line. The time occupied in charging the condenser is that required for one of the metal teeth of the disk *A* to pass under the spring *b*, and the strength of any particular charge will depend upon the character of the movement taking place in the instrument *T* during such time. The time required to discharge the condenser, on the other hand, is very much less than that occupied in charging it, the discharge being practically instantaneous whatever the strength of the charge, while the charging is gradual and consumes an appreciable period of time. It follows that the current in line *L* is made up of a succession of sharp, quick, and absolutely-distinct impulses formed by the condenser-discharges. At the same time it is found to reproduce in the receiver *R* the words or sounds directed into the instrument *T*. Such an apparatus may be put up in a commercial form in the manner shown in Fig. 1, in which the various devices are inclosed in boxes or cases secured to a board *A''*.

In the drawings, *T* is the instrument for varying or modifying the current to be sent into the condenser. *B* is the battery-box. *A* contains the circuit-shifter, and *D* the condenser.

It is desirable for the attainment of the best results that as much of the current in the local as is practicable should be transferred to the line in the above-described man-

ner. I therefore find it advantageous to employ a number of disks like the disk *A*, above described, and to multiply the other appliances accordingly. In Fig. 3 I have shown an apparatus of this kind containing six of such disks. This device consists of six independent metal disks or wheels (designated by the numerals 1 to 6) mounted on and secured to a common shaft. The shaft is mounted in a strong frame and carries a pulley *G*, by means of which it is rotated. The periphery of each wheel is cut with teeth, the spaces between which are filled in with insulating material *d*. Three brushes or spring-contacts bear on each wheel—two on the periphery and one on the shoulder *F*. One of the wires of the local circuit *S* is electrically connected to the three springs *o p q*, and the other wire is similarly connected to the springs *r s t*. In like manner one terminal of the main line is electrically connected to springs *u v w*, and the other to springs *x y z*. The terminals of the three condensers *D D' D''*, are respectively connected to springs *i l j m* and *k n*. Each wheel has twenty-four metallic teeth and a corresponding number of insulating-spaces, each of which is slightly more than twice as long as a metallic tooth. The wheels are insulated from one another, and so set that the teeth and insulating-spaces on wheels 1 2 3 correspond exactly in position with those on the three remaining wheels, so that, for instance, while brush *u* is in contact with a metallic tooth on wheel 1 brush *x* will be in contact with a metallic tooth on wheel 4, and so on for all the others. The relative length of the insulating and conducting portions of the peripheries of the wheels brings all the brushes *u v w x y z* upon insulation for a moment at the instant when any two of the brushes, as *u z*, have passed over the metal teeth, or seventy-four times for each revolution of the shaft. The same is true of the brushes *o p q r s t*. From this it follows that only one condenser can be charged or discharged at the same time. The positions of the brushes *o p q r s t* are also adjusted so that both of the brushes bearing on the periphery of any one of the wheels may never be in contact with metal teeth at the same time. As a result of this the local circuit *S* is never in direct connection with the line *L*. This disposition of the parts, together with the action of the instrument, will be more clearly understood by reference to Fig. 4, in which the apparatus is shown diagrammatically, corresponding parts being similarly designated.

Assuming that the wheels are being rapidly rotated from a suitable source of power, their action in transferring the current of circuit *S* to the line *L* will be as follows: At a given point of time during the revolution of the wheels the brushes will be in the positions shown in Fig. 4—that is to say, the brushes *o r* bear on the metallic teeth of wheels 1 and 4. The metal portions of these wheels being in constant electrical connection through

brushes $i l$ with the terminal of condenser D , the latter will receive a charge, there being no other path for the current through the said wheels, inasmuch as the line-brushes $u x$ are at the time on insulation. The next pair of wheels 2 and 5 during this time are out of action, since both sets of brushes $p s$ and $v y$ are on insulation, so that the condenser D' is neither receiving nor giving up a charge. 10 The corresponding position of the third pair of wheels brings the line-brushes $w z$ on the metal teeth and the local brushes $q t$ on insulation. The condenser D'' , being thus connected with the line, discharges into the same. 15 In this manner as the wheels rotate with the shaft the condensers are alternately charged from circuit S and discharged into line L , one condenser, as D , being charged while a second is discharging and the third being out. 20 So by the further rotation of the wheels condenser D' will next be charged, condenser D discharged, and condenser D'' cut out, and so on. The independent impulses, pulsations, or discharges thus thrown onto the line 25 produce in an ordinary telephonic receiver the words or sounds directed into the instrument T .

In illustration of another way in which the principle may be carried out I now refer to Fig. 5. In this case three wheels 7 8 9, similar to the three above described, are mounted on the shaft and insulated from one another. Three brushes or contact-springs bear upon each wheel—two on the periphery and the other on the circular shoulder or flange. Of the two brushes which bear on the periphery one will be on metal, the other being on insulation, or both may be on insulation, but never both on metal at the same time. The brushes $r s t$ are electrically connected to one branch of the main line L . The brushes $o p q$ are connected to one branch of the local circuit S , and the branches $i j k$, respectively, to one of the terminals of the three condensers $D D' D''$. 45 The opposite terminals of these condensers are connected by wires $l' m' n'$ to the conductor $S L$, which is connected to the two circuits S and L . The action of this apparatus is as follows: The current in circuit t' , properly varied or modified by the instrument T , induces currents in the secondary coil C' . At the moment when the disks or wheels are in the positions shown the brushes g and k , being on metal, complete the circuit 50 of the secondary coil C' through the condenser D'' , which at this moment, therefore, receives a charge. Both of the brushes $s p$ being on insulation the condenser D' is out of action entirely, while at the same time the 55 circuit of the main line is complete through the condenser D , since brush r is in contact with the metal portion of the wheel 7. A like result follows from the further rotation of the wheels, one condenser being charged while another is discharging, and the third being out of circuit. It will result, as in the former cases, that the receiver will be acted upon by

a series of separate and independent electrical impulses.

In Fig. 6 is shown an instrument for accomplishing the same results and in which the requisite conversion of the current is effected by means of a vibrator acting in combination with a condenser. P is an insulating base-board provided with five binding-posts. Upon this base is mounted an electro-magnet M , in front of whose poles is a vibrating magnetic strip or reed N , one end of which is set in a conducting-post M' . Ordinary devices are used to maintain the reed in vibration—that is to say, an adjustable contact-stop N' is placed in front of the magnet M and the circuit-connections made from a battery B' to the binding-posts 13 and 14, which are connected by the conductor $b' b'$, the coils of magnet M , the post M' , reed N , and stop N' . This circuit being made and broken between the reed and stop N' the reed, by the interrupted attraction of the magnet, is maintained in rapid vibration. The free end of the reed has platinum contact-points on opposite sides, and vibrates between the ends of the two levers E' and F' . These levers are made adjustable by screws H' , but are firmly held in their adjusted position, as by means of the springs G' . For use these levers are adjusted close to the platinum contacts, but leaving a slight space on each side, so that when the reed is vibrated by the magnet the said contacts may touch the levers alternately. As in previous figures, the circuit t' contains the battery B , the instrument T , and the primary C of an induction-coil. One wire from the secondary leads through binding-post 10, which connects with lever E' , and the other is connected to one 100 terminal of a condenser D . The main line or circuit is partially formed by the conductors $L L$, one of which leads from the receiver R to the same terminal of the condenser, to which is connected wire S , and the other to binding-post 12, which is connected to lever F' . A path common to both circuits is formed by the conductor $S L$ from the opposite terminal of the condenser D to binding-post 11, which is in permanent electrical connection 105 with the post M' and reed N . It results from this arrangement that by the vibration of the reed N , as above described, the local circuit S and line-circuit L are alternately completed through the condenser D , but are never connected directly together. Any impulses or currents on the main line, therefore, must come from the local entirely through the charging and discharging of the condenser D , and, secondly, since the time occupied by 110 the condenser in discharging is very much less than that required to charge it, it follows that whatever be the character of the currents in the local the current in the main line, which causes the receiver R to reproduce the words 115 spoken into the instrument T , is made up of a rapid succession of separate and distinct impulses or pulsations. If, in the case of this instrument, the bars or levers $E' F'$ are ad-

- justed so far apart that the vibrating reed does not touch them, the reed gives off a musical tone; but if the reed forcibly strikes the levers the tone is broken and an effect 5 produced in the receiver R which resembles the well-known "frying" sound often heard in telephone-receivers. It is not loud enough, however, seriously to interfere with the sounds transmitted through the line.
- 10 The operation of the instrument is readily understood from the foregoing. By contact of the lever E' and reed N the condenser D receives a charge. Then by the shifting of the reed and the contact of lever F' there- 15 with this charge is thrown on the main line. Such charges and discharges following in rapid succession reproduce in the receiver the words and sounds directed into the instrument T.
- 20 Having now explained the nature of my invention and the means by which it may be carried into effect, I would state that I do not claim, broadly, the combination, with a tele- 25 phonetic circuit, of one or more condensers, as condensers have heretofore been used in various ways in telephony. For example, I do not claim as my invention the combination of a condenser with an induction-coil to prevent
- 30 sparking, nor those systems in which the over- flow of a condenser is sent along with the battery-current, nor those in which the condenser is simply connected up in line to di-

vide it, nor those in which a condenser is used either as a transmitter or a receiver.

The method of telephoning or transmitting 35 articulate speech and other sounds involved herein I have made the subject of another application, Serial No. 283,785, filed August 25, 1888, and do not claim it herein.

What I claim is—

1. In a telephone system, the combination, with a local circuit in which circulates a current varied or modified to correspond to the elements or waves of the vocal or other sounds to be transmitted, of a main or line circuit, a 45 condenser or series of condensers, and one or more circuit-shifters for alternately connecting the condenser or the series of condensers successively to the two circuits, as set forth.
2. In a telephone system, the combination, 50 with an induction-coil, a battery, and an instrument for varying or modifying the current to correspond to the elements or waves of the vocal or other sounds to be transmitted, included in the primary circuit thereof, of a 55 main or line circuit, one or more condensers, a circuit shifter or shifters adapted to alternately connect the condenser or condensers successively to the secondary and main circuits, as and for the purposes set forth.

JAMES W. McDONOUGH.
